(57) CLAIM

The ornamental design for a mascot figure, as shown and described.

DESCRIPTION

FIG. 1 is a front perspective view of a first embodiment of a mascot figure showing my new design.

FIG. 2 is a rear perspective view of the mascot figure of FIG. 1.

FIG. 3 is a front view of the mascot figure of FIG. 1.

FIG. 4 is a rear view of the mascot figure of FIG. 1.

FIG. 5 is a left side view of the mascot figure of FIG. 1.

FIG. 6 is a right side view of the mascot figure of FIG. 1.

FIG. 7 is a top view of the mascot figure of FIG. 1.

FIG. 8 is a bottom view of the mascot figure of FIG. 1.

FIG. 9 is a front perspective view of a second embodiment of a mascot figure showing my new design.

FIG. 10 is a rear perspective view of the mascot figure of FIG. 9.

FIG. 11 is a front view of the mascot figure of FIG. 9.

FIG. 12 is a rear view of the mascot figure of FIG. 9.

FIG. 13 is a left side view of the mascot figure of FIG. 9.

FIG. 14 is a right side view of the mascot figure of FIG. 9.

FIG. 15 is a top view of the mascot figure of FIG. 9.

FIG. 16 is a bottom view of the mascot figure of FIG. 9.

FIG. 17 is a front perspective view of a third embodiment of a mascot figure showing my new design.

FIG. 18 is a rear perspective view of the mascot figure of FIG. 17.

FIG. 19 is a front view of the mascot figure of FIG. 17.

FIG. 20 is a rear view of the mascot figure of FIG. 17.

FIG. 21 is a left side view of the mascot figure of FIG. 17.

FIG. 22 is a right side view of the mascot figure of FIG. 17.

FIG. 23 is a top view of the mascot figure of FIG. 17; and,

FIG. 24 is a bottom view of the mascot figure of FIG. 17.
